UNITED STATES PATENT OFFICE

163,881

COMBINATION MERCHANTISE DISPLAY CASE AND CASHBOX

Alex Jay Liberman, Los Angeles, Calif.

Application July 22, 1949, Serial No. 4,063

Term of patent 7 years

(Cl. D80--11)

To all whom it may concern:

Be it known that I, Alex Jay Liberman, a citizen of the United States, residing at 5675 West Washington Boulevard, Los Angeles, county of Los Angeles, State of California, have invented a new, original, and ornamental Design for a Combination Merchandise Display Case and Cash Box, of which the following is a specification, reference being had to the accompanying drawing, forming a part hereof:

Figure I is a perspective view of a combination merchandise display case and cash box showing my new design.

Figure V is a perspective view of a portion of my combination merchandise display case and cash box with a portion broken away to show the interior.

The dominant features of my design resides in the portions shown in full lines.

I claim:

The ornamental design for a combination merchandise display case and cash box, as shown and described.

ALEX JAY LIBERMAN.
